SAMUEL C. BOND, OF HOLLY OAK, DELAWARE

MACHINE FOR FILLING AND CAPPING BOTTLES

Application filed December 9, 1922. Serial No. 605,955.

This invention relates to improvements in machines for filling and capping bottles, the invention being more especially designed for incorporation in a foot power machine of 5 that type wherein the bottles may be filled with an aerated or carbonated water, either with or without a desired percentage of syrup, the syruping of one bottle preceding simultaneously with the filling of another 10 bottle with the aerated or carbonated liquid, although features of the invention may be incorporated in machines operated by power, as will be apparent to those skilled in the art.

The objects of the invention are to provide 15 a machine which is simple both in its construction and operation and with which bottles may be rapidly filled and capped with a minimum of labor on the part of the attendant, and also to provide a machine wherein 20 the pressure on the bottle during the filling and capping stages is decreased as compared with prior machines, whereby the danger of breakage is greatly reduced.

A further object of the invention is to provide 25 an improved control mechanism whereby invariable and exact measurements or volumes of syrup may be supplied at each filling and capping operation, without further attention on the part of the attendant than 30 that necessary to place the bottles in position and transfer the same to the capping station.

Referring to the accompanying drawings,—

Figure 1 is a side elevation, partly broken 35 away and in section of a machine embodying the present improvements.

Fig. 2 is a sectional elevation looking at the front of the filling head, valve and syruping device, the section being substantially on the 40 line 2—2 of Fig. 1.

Fig. 3 is a top plan view of the parts shown in Fig. 2, with the casing for the valve handle spring in section.

Figs. 4, 5 and 6 are sectional elevations in 45 a plane substantially at right angles to the sectional plane of Fig. 2 and showing the filling and capping head in different positions with relation to the bottle, it being understood in this connection that, while the machine is shown with a stationary filling head

and a movable bottle support, the converse arrangement might be employed as is common in this art.

In the convenient and handy form of the machine adopted for illustrating the invention a base stand 1 of conventional form is provided within which is mounted a sliding lifter 2, adapted to be elevated or allowed to descend under the control of a treadle 3 pivoted in the base and connected with the lifter 55 through the medium of a link 4 and suitable pivotal connections at the ends of the link. The body of the lifter is preferably tubular or chambered at the upper end for the reception of a screw stem 5 which latter at its upper end carries the bottle support 6 and by its adjustment the height of the said support with relation to the filling and capping head 60 may be regulated to suit different sized bottles.

Extending upwardly from the base stand 70 are front and rear columns 7 and 8, respectively, which, at their upper ends, support the filling head 9 in fixed position, and upon the rear column 8 there is mounted a 75 sleeve 10, the lower end of which rests on or is adapted to be elevated by an extension on the lifter 2, as shown in Fig. 1. At its upper end this sleeve is provided with a shoulder or enlargement for co-operating with the lower 80 end of an actuating rod which through mechanism to be presently described performs the function of closing the throat gasket around the mouth of the bottle during the filling operation without, however, maintaining the 85 pressure on the bottle during the application of the capping pressure, as will be presently explained.

The filler head has within it a vertically 90 movable cylindrical member which may be conveniently termed a valve head 11 and within this valve head there is a vertically movable plunger 12 held down by the yielding pressure of a heavy spring 13 confined between the upper head or end of the plunger 95 and a valve head nut 14 which is in the form of a cylinder screw-threaded on the upper end of the valve head and having an overhanging skirt 14^a which fits around a cylindrical projection of the filler head, as shown in the sec- 100

tional views. At its lower end the valve head constitutes a filler chamber adapted to house the usual tapering cap-contracting throat 15, together with the yielding dogs or fingers 16 for holding the cap in position ready for application to the bottle mouth. Also working within the large plunger 12 is a smaller spring-pressed plunger 17 surmounted by a light spring shown in dotted lines in Fig. 6 10 and the relative movement of which is limited by a pin 18.

The lower end of the filler head is provided with an annular seat for the throat gasket 19, such seat being preferably formed in a bottom cap or annulus 20, threaded on the lower end of the filler head. This throat gasket is confined between the seat so formed and a seat on the valve head, which latter seat may conveniently be extended transversely or the 20 gasket provided with a top washer of approved form.

The relation of these parts is such that, when the valve head is depressed, the throat gasket 19 will be compressed and the aperture therethrough correspondingly reduced in diameter, as will be readily understood by a comparison of Figs. 4 and 5. For performing this function in proper co-ordination with the upward movement of the bottle on 25 its support, the following mechanism is provided: An actuating rod 65 is mounted to slide vertically without rotation in a suitable guide-way in the head 9, as shown in Figs. 4 to 6. At its lower end this actuating rod carries an adjustable projection, conveniently in the form of a set screw 66 with which the head or shoulder on the sleeve 10 is adapted to contact for lifting the actuating rod with relation to the head in consonance with the movement of the bottle with relation to the head. The timing of the movement of the actuating 30 rod may be varied by adjusting the part 66 so as to effect the operation of the parts controlled by the actuating rod in proper sequence with the advance and filling of the bottle. The actuating rod 65 is provided with a primary pawl 21 pivotally mounted and adapted for co-operation with a spring-pressed plunger 22, whereby it will be retained in either of the positions shown in 35 Figs. 4 and 5 and for co-operation with this primary pawl there is provided an eccentric 23 pivotally mounted in the filler head and having on one side a projection 24 which will co-operate with the pawl for turning the eccentric from the position shown in Fig. 4 to that shown in Fig. 5, whenever the actuating rod is elevated. The eccentric 23 co-operates with a secondary pawl 25 which at its lower 40 end takes a bearing on the valve head 11 and consequently, when turned from the position shown in Fig. 4 to that shown in Fig. 5, the valve head is depressed to compress the throat gasket and reduce the size of the aperture therein.

In moving from the position shown in Fig. 4, to that shown in Fig. 5, a second projection 26 on the eccentric passes in through an opening in the side of the valve head and rests upon or immediately over a shoulder formed by the lower head of the large plunger 12 and in position for that plunger upon its elevation to restore the eccentric to substantially the position shown in Fig. 4, or to turn it sufficiently in that direction to permit of the elasticity of the throat gasket completing its movement. When, however, the eccentric is turned into the position shown in Fig. 5 its center of movement reaches or slightly passes the neutral point, and hence the valve head will be held down until a reverse movement of the eccentric is effected.

By reference to Figs. 2 and 3, it will be seen that the valve head is provided at one side with a valve casing 27 adapted to work vertically in a slot in the filler head in unison with the valve head, and this valve casing at its inner end communicates through an inwardly and downwardly inclined passage 28 with the filling chamber above the throat gasket 19.

The valve casing 27 contains a valve mechanism adapted to be operated by the valve handle 29 to admit carbonated water under pressure or to permit of the snifting operation which is necessary in filling bottles with liquids having gas under pressure therein. The carbonated water or the liquid under pressure is supplied through a rear fitting 30, Fig. 3, from any suitable source of supply, and its entrance into the filling chamber is normally prevented by a tubular valve 31 seating against the inner end of the valve casing or a suitable seat formed in the valve head, and if desired having an intermediate fiber washer 32, said valve being held against its seat by a spring 33. The valve is adapted to be brought away or lifted from its seat by the head of a secondary valve plunger 34 which at its outer end is connected with the valve end 35 controlled by the handle 29. The plunger 34 is tubular and provided with connected ports 36 in proximity to its ends, the port near its inner extremity being so located that when the plunger is pushed inwardly it will be opened to the filling chamber, but when the plunger is drawn back until its head seats against the fiber washer on the main valve, the port will be closed.

The port at the outer end of the plunger is in communication with the atmosphere or waste pipe and as a convenient and desirable construction the valve casing is provided with an exhaust connection 37 which communicates through a suitable hose connection 38 with the upper end of the tubular rear column 8, whereby any snifting exhaust will be conveyed down through that rear column and escape at an unobjectionable point. For preventing communication between the liquid inlet and the snifting exhaust the valve casing

is provided with a front packing washer 39 held to its seat and in position to engage the tubular portion or sleeve of the main valve by a transversely apertured long follower 40 and the projection of the valve end 35 with which the plunger is connected is surrounded by a packing washer 41 which is held in place by a short follower and lock nut 42. The whole arrangement is such that when the 10 valve handle is moved in one direction or so as to draw the valve end outwardly, the main valve will be lifted from its seat and carbonated liquid allowed to enter the filling chamber, but upon moving the valve handle 15 in the opposite direction, the main valve will be seated or allowed to remain on its seat and the supplemental valve will be opened, putting the filling chamber into communication with the exhaust through the two ports in 20 the snifting valve plunger.

The filler head is provided with a pad for the attachment of a bracket 43 in which the syruping device is mounted. This syruping device comprises preliminarily a measuring cylinder 44 which is vertically movable in the bracket but held against rotation therein, and within the cylinder there is a weighted piston 45, the upward movement of which piston in the cylinder is limited by an 25 accurate stop mechanism which is readily adjustable from the exterior so as to regulate the volume of syrup accommodated in the cylinder in any one charge. For admitting syrup to the cylinder, it is provided 30 on the rear side with a syrup supply fitting 46, Fig. 3, connected with any suitable source of supply and having sufficient hydrostatic head to elevate the piston. This syrup supply fitting 46 communicates with the interior 35 of the cylinder through an inlet port 47, Fig. 2, opening downwardly and adapted to be closed at certain times, if so desired, by a vertically movable valve 48. When the valve is in the position shown in Fig. 2 the inlet 40 port 47 is in open communication through the intercommunicating passage 49 with the cylinder below the piston, and the entering syrup will raise the piston to the limit permitted by the stop mechanism. The syrup is permitted to escape from the cylinder into the 45 bottle when the valve 48 is lifted by contact with the bottle and for this purpose the valve 48, while normally seating so as to close the exit, will, when raised, permit the syrup to flow into the discharge port 50 and out at the lower end of the valve stem. The 50 lower or external end of the valve stem is provided with the usual cone-shaped seat for the mouth of the bottle and is normally held so as to close the exit port by means of a coil 55 spring 51 confined between the conical mouth piece and a recess in a valve nut 52 screwing into the lower end of the cylinder.

The stop mechanism for regulating the volume of syrup measured, consists of a cylin-

drical gage nut 53 screwing into the upper end of the cylinder and at its lower edge forming the stop for arresting the upward movement of the plunger or piston. The relation of the pitch of the screw threads to the 70 size of the cylinder is such that a complete turn of the gage nut will vary the size of the measuring chamber to accommodate a definite volume of liquid, say, for example, one-fourth ounce, and gage marks are provided 75 on the nut for indicating each particular rotation and the volume which will be measured at each point. In addition, the periphery of the nut and the cylinder with which it cooperates are divided into eight divisions, 80 each of which indicates one thirty-second of an ounce, and in order to retain the nut accurately and positively in its adjusted position with relation to the cylinder, vertical apertures are formed in the threaded portion 85 of the two members, as shown at 54, in Fig. 3, for the accommodation of a locking pin 55, thus providing for the most accurate adjustment and the retention of the parts in their adjusted position with the greatest degree 90 of certainty.

As a convenient construction the piston proper is preferably a relatively heavy body, as shown at 45, and this is surmounted by a leather packing 56 confined between the body 95 45 and a follower 57, the parts being held together by a screw-threaded handle 58 located within the cylinder and gage nut, as shown clearly in Fig. 2.

The weight of the piston effects the discharge of the measured quantity of syrup when the exit valve is opened by the engagement of the bottle mouth with the seat at the lower end of the valve, and by making the cylinder itself vertically movable in its 100 bracket, any variation in the height of the bottle is readily accommodated and the only precaution necessary to observe is that the spring holding the valve closed should be of less strength than that required to elevate the 105 cylinder. In other words, the weight of the cylinder is largely in excess of the strength of the spring and sufficient not only to overcome the spring but also to overcome the hydrostatic head of the syrup which would tend 110 to reseat the valve or to open the valve when moved sufficiently far to close the inlet port.

It will be understood, of course, that the 115 filler head spring 13 is a heavy spring and sufficient to prevent the pressure of the carbonated water from unseating or moving the plunger 12 upwardly, although as precautionary measures against the escape of liquid in this direction, the valve head nut is closed at the upper end and the plunger 12 is adapted 120 to seat against a leather washer 59.

In operation, the attendant, having placed the requisite quantity of syrup in one bottle, transfers that bottle on the bottle support to the position for co-operating with the filler 125

head, and a second bottle is placed in position for co-operation with the syruping device. The treadle is now depressed, raising both bottles, that in position to co-operate with the 5 filler head moving from the position shown in Fig. 4 to the position shown in Fig. 5. Preliminary to this, the operator has, of course, as usual, placed a cap within the filler head, as shown in the drawing. In moving 10 up from the position shown in Fig. 4 to that shown in Fig. 5, the lifter has advanced the sleeve and the actuating rod, the latter, through the operation of the pawls and eccentric, has forced the valve head down from the position shown in Fig. 4, to the position 15 shown in Fig. 5, thereby compressing the throat gasket and reducing the diameter of the opening therein to a point where the bottle will form a sealing engagement. The 20 resistance offered by the bottle to further movement will tell the operator when to stop, and he then manipulates the valve handle so as to first admit carbonated water and when the pressure is equalized he moves the handle in 25 the other direction, so as to permit of the escape of air, and these operations are repeated until the bottle is properly filled. When 30 filled, a further movement of the treadle forces the bottle up through the throat gasket and 35 into contact with the sealing cap. The first contact with the sealing cap is caused by the resistance of the light spring-pressed plunger and a continued upward movement of the bottle performs several functions. As the 40 bottle enters the contracting throat 15 it begins to elevate the main plunger 12, and at this instant the main plunger 12 begins to turn the eccentric backwardly, with the result that pressure on the throat gasket is relieved. In proportion to the further 45 advance of the bottle and before the pressure required to lock the cap is exerted, the pressure on the throat gasket is entirely relieved and consequently the only pressure exerted 50 on the bottle is that required to lock or deform the cap. This arrangement relieves the bottle of a very large proportion of the pressure exerted in prior machines during the final capping movement, as, with the present 55 machine, there is no throat gasket pressure at this time, and consequently, a large percentage of saving is made in broken bottles or containers, or what is equally important, it becomes possible with this machine to employ bottles or containers of relatively lighter 60 gage.

What I claim is:

1. In a bottle filling and capping machine, a filler head having means for applying and 65 locking a bottle cap on the mouth of a bottle by a relative movement of the parts toward each other, an elastic, normally distended contractile throat gasket, means for contracting the gasket into sealing contact with the 70 bottle, and means actuated by engagement 65

with the bottle for operating to release the throat gasket when the head and bottle are given a relative movement to lock the cap on the bottle.

2. In a bottle filling and capping machine, 70 a filler head having means for applying and locking a bottle cap on the mouth of a bottle by a relative movement of the bottle and head toward each other, an elastic contractile throat gasket, a relatively movable member 75 carried by the head for contracting the gasket to form a sealing contact with the bottle, means for moving said member into gasket contracting position, and means actuated by the bottle for releasing said member to permit the gasket to expand during the relative movement of the bottle and head toward each other.

3. In a bottle filling and capping machine, 80 a filler head having means for applying and locking a bottle cap on the mouth of a bottle by a relative movement of the bottle and head toward each other, an elastic contractile throat gasket, a relatively movable member 85 carried by the head for contracting the gasket to form a sealing contact with the bottle, a pawl engaging said member, an eccentric cooperating with said pawl for holding said member in gasket contracting position during 90 part of the relative forward movement of the bottle, and means actuated by the bottle during the latter part of its relative forward movement to impart a return movement to said pawl and eccentric to release 95 said gasket and permit it to expand. 100

4. In a bottle filling and capping machine, 105 a filler head having means for applying and locking a bottle cap on the mouth of a bottle by a relative movement of the bottle and head toward each other, a normally distended elastic contractile throat gasket, a relatively movable member carried by the head for contracting the gasket to form a sealing contact with the bottle, means for moving 110 said member to contract the gasket as the bottle is brought into gasket engaging position, said means comprising a lock for retaining the gasket contracted, and means for releasing such lock during the relative movement of the parts for locking the cap on the 115 bottle.

5. In a bottle filling and capping machine, 120 a filler head having means for applying and locking a bottle cap on the mouth of a bottle by a relative movement of the body and head toward each other, an elastic contractile throat gasket, a relatively movable member 125 carried by the head for contracting the gasket to form a sealing contact with the bottle, means for moving said member to contract the gasket as the bottle is brought into gasket engaging position, said means comprising a lock for retaining the gasket contracted, a yielding plunger within the head for co-operation 130 with the bottle cap in locking the 130

same on the bottle, and a shoulder on said plunger for co-operation with the lock to release the gasket during the application of cap locking pressure on the bottle.

5. In a bottle filling and capping machine, a filler head having means for applying and locking a bottle cap on the mouth of a bottle by a relative movement of the body and head toward each other, an elastic contractile 10 throat gasket, a relatively movable member carried by the head for contracting the gasket to form a sealing contact with the bottle, a relatively movable actuating rod, a pawl carried by said rod, an eccentric mounted on the head with which said pawl co-operates, and a secondary pawl actuated by said eccentric for advancing said relatively movable member to contract the gasket during the relative forward movement of the bottle into 15 20 gasket engaging position, the pawl on said actuating rod being movable out of engagement with the eccentric during the final relatively forward movement of the bottle for applying the cap thereto.

25. 7. In a bottle filling and capping machine, a filler head having means for applying and locking a bottle cap on the mouth of a bottle by a relative movement of the body and head toward each other, an elastic contractile 30 throat gasket, a relatively movable member carried by the head for contracting the gasket to form a sealing contact with the bottle, a relatively movable actuating rod, a pawl carried by said rod, an eccentric mounted on the head with which said pawl co-operates, a secondary pawl actuated by said eccentric for advancing said relatively movable member to contract the gasket during the relatively forward movement of the bottle into 35 40 gasket engaging position, the pawl on said actuating rod being movable out of engagement with the eccentric during the final relatively forward movement of the bottle for applying the cap thereto, and a plunger 45 mounted in said head in position to be moved by the bottle and co-operating with said eccentric to release the secondary pawl and permit the gasket to expand.

8. In a bottle filling and capping machine, 50 a filler head having a port for admission of the liquid to be bottled, combined filling and snifting valves controlling said port, said valves comprising concentric valve members movable in unison in one direction for filling, 55 the inner member being movable independently in the opposite direction for snifting, and a controlling handle connected with the inner member whereby the movement of the handle in one direction admits filling fluid, 60 and the movement of the handle in the opposite direction cuts off the supply of filling fluid and opens the snifting valve member.

9. The combination with a bottle filling and capping machine, of a filler head having 65 a port therein, a combined filling and snift-

ing valve controlling said port comprising a tubular filling valve member, a snifting valve member located within said tubular valve member and having an enlargement for co-operation with the filling valve member to open the latter when moved in one direction, a port opened by its movement in an outward direction for snifting, and a handle connected with said snifting valve member for filling and snifting respectively by movements in opposite directions. 70 75

10. The combination with a bottle filling and capping machine, of a filler head having a port therein, a combined filling and snifting valve controlling said port comprising concentric members movable in opposite directions for opening the ports controlled thereby, one of said members having a projection co-operating with the other member to open the latter when the first mentioned member 80 is moved in a direction to close the port controlled thereby, and an operating handle connected with said last mentioned member. 85

11. The combination with a bottle filling and capping machine, of a filler head having 90 a port therein, a combined filling and snifting valve controlling said port comprising a tubular filling valve, a spring for advancing said valve to closed position, a packing surrounding said valve, an internal snifting 95 valve having a head for co-operation with the filling valve for opening the latter, and a port opened by movement of the snifting valve in the opposite direction, a packing surrounding the snifting valve stem, a snifting valve exhaust duct communicating with the snifting valve between said packings, and a handle for operating the snifting valve in one direction for snifting and in the opposite direction for opening the filling valve 100 105 for filling.

12. In a bottle filling and capping machine, a filler head, means comprising a plunger for applying caps to the bottle, a gasket to form a sealing contact with the bottle, means for contracting the opening in the gasket, and means controlled by the movement of said plunger for permitting the expansion of the gasket opening to its original diameter. 110

13. In a bottle filling and capping machine, a filler head, means for applying caps to a bottle, a gasket to form a sealing contact with the bottle, means for contracting said gasket, and means actuated by the bottle for releasing said gasket to permit the expansion thereof. 115 120

SAMUEL C. BOND.
